[57] CLAIM

The ornamental design for a back wall for a baseball
glove, as shown and described.

DESCRIPTION

FIG. 1 is a front elevational view of the back wall for a
baseball glove showing my new design;

FIG. 2 is a bottom plan view thereof;

FIG. 3 is a left side elevational view thereof; and

FIG. 4 is a right side elevational view thereof.

The broken line showing of the finger portions of the
glove is for illustrative purposes only.

FIG.1

FIG.2

FIG.3

FIG.4
